FREDERICK M. MATTICE, OF CLEVELAND, OHIO.

Letters Patent No. 104,046, dated June 7, 1870.

IMPROVEMENT IN SOCKET-PIPE MACHINERY.

The Schedule referred to in these Letters Patent and making part of the same

I, FREDERICK M. MATTICE, of the city of Cleveland, county of Cuyahoga, State of Ohio, have invented certain Improvements in Socket-pipe Machinery, of which the following is a full description, reference being had to the accompanying drawing and to the letters of reference marked thereon, in which drawing—

Figure 1 is a perspective view of the device with the several parts in position.

Figure 2 is a perspective view of the same with the carriage in a vertical position, and showing the position of a pipe after it is made and previous to its removal for drying.

Figure 3 is an elevation in perspective of a pipe standing upon a drying-board, with the ring partially removed, and,

Figure 4 is an elevation in perspective of a drying-board with the core of the socket-die upon it.

Like letters of like kinds represent like parts in each figure.

The object of my invention relates to the forming of the sockets upon the ends of draining-pipes of clay, for the purpose of uniting them, and the apparatus used for conveying said pipes away from the dies without injury, and to a convenient and secure apparatus for removing said pipes to the drying-ground; and

It consists in the arrangement of the devices employed in making the socket, consisting of a ring upon the die-plate, a core attached to a drying-board, and a movable outside ring for shaping the socket in a movable carriage, capable of being tilted up and caused to assume a vertical position, and in the combination of the devices used for the transportation and preservation of the pipes when made, consisting of the covering-ring and the drying-board above named.

For the better comprehension of my invention, the whole device will be understood as forming the front of a drain-pipe machine for making pipes of clay, the rear part of my device forming a part of the chest into which the clay, after preparation in a suitable pug-mill, is forced through proper openings, in the formation of such pipes,

In the drawing—

A represents a die-plate of suitable material, forming the front of the clay-chest above referred to, which plate has an opening, P, of proper size for the diameter of the pipe desired, having a suitable core in its center, held in position by one or more pins.

Around the periphery of this opening is a ring, *ll*, which may be cast with the plate or secured thereto in any suitable manner.

The inner sides of this ring are beveled inwardly with a concave curve; the face of the ring is flat, parallel with the vertical plane of the die-plate, and of

a width equal to the thickness of the pipe desired, and the line of the outer periphery is at right angles with the vertical plane of the die-plate.

B represents a cylindrical ring provided with ears *a* on each side, said ears having pins projecting from them.

The internal size of this ring corresponds with the exterior of the ring *ll*, over which it fits closely, and its use is to give support and outside shape to the socket of the pipe in the process of making it.

C shows a drying-board provided at its ends with holes for the pins upon the ears of the ring B, and having upon its center, and secured to it, a core D, corresponding in size and form with the interior of the socket to be made upon the pipe.

A lever E, composed of two legs standing at right angles, is pivoted, at their point of junction, to suitable bearings, F, secured to the top center of the die-board A, directly over the center of the pipe-opening, so that a downward forward pressure upon the upper leg of the lever would bring its lower leg down over the center of said opening.

A carriage, G, provided with an endless belt, J, running over suitable rollers, I, which rollers are hollowed out in their centers, traverses upon rollers journaled into the sides, H, of the frame which supports the carriage.

The endless belt is composed of bars of wood placed in parallel lines at a little distance from each other, and the whole is covered loosely with suitable cloth. The carriage is provided upon its outside near the center longitudinally with trunnions, K, which trip against suitable stops O upon the front ends of the side-pieces H of the frame, so that the carriage, when run forward, may be tipped up and stand in a vertical position. Any proper pin, connected by a cord attached to the side-piece H, may be inserted in a hole on the top of said side-piece, in front of the trunnion K, so as to keep said carriage in position upon said frame.

The operation of this device is as follows, viz:

The pipe being forced out through the opening in the die-plate A, and its front properly squared off, and the ring B being attached by its pins to the drying-board C, with the core D upon it, the smaller part of the core is placed within the front opening of the pipe, the lever E is pressed down upon the outside of the drying-board C, and the core D is pressed into the end of the pipe, forming a socket upon it. The lever is then released and the pipe forced out through the opening a desired distance, the edge of the drying-board and the ring B resting upon the endless belt, and moving forward with it, until the pipe has issued the distance desired for its length, when it is cut off close to the die-plate. The pipe

thus formed is pushed forward a little, until the trunnion K of the carriage strikes the stops, O, when the carriage is turned up, which permits the pipe, then standing in a vertical position, to stand upon the drying-board, which in turn rests upon the ground or upon a platform. The pipe is then removed to the drying-ground, the ring B is taken off, and the pipe suffered to remain until sufficiently hardened to preserve its form when the core and drying-board may be taken away.

The advantages of these devices are obvious, when the size, weight, and fragility of the pipes, and the necessity of nicety in construction and care in handling are considered.

Having thus fully set forth the nature and merits of my invention,

What I claim as new, and desire to secure by Letters Patent, is—

1. The combination of the drying-board C, provided with the core D and the ring *ll*, with the opening P in the die-plate provided with a suitable core, the ring B, and the lever E, when constructed, arranged, and operating as and for the purpose set forth.

2. The carriage G, provided with the endless belt J and with the trunnions K, in combination with the frame H provided with the rollers I, when constructed, arranged, and operating as set forth.

3. The combination of the ring B, provided with ears *a* having pins attached to them, and the drying-board C having the core D attached to it, when arranged for the purpose of retaining the pipe-socket in shape and preserving the same from injury.

FREDERICK M. MATTICE.
